(57) **CLAIM**

The ornamental design for an expandable wheel, as shown and described.

DESCRIPTION

FIG. 1 is a perspective view of an expandable wheel showing our new design in an open position and in use; FIG. 2 is a perspective view of the expandable wheel in an open position;

FIG. 3 is a left side view thereof;

FIG. 4 is a right side view thereof;

FIG. 5 is a front view thereof;

FIG. 6 is a perspective view of the expandable wheel in a closed position;

FIG. 7 is a left side view thereof;

FIG. 8 is a right side view thereof;

FIG. 9 is a front view thereof;

FIG. 10 is an exploded view of the expandable wheel; and, FIG. 11 is a perspective view of an expandable wheel in a closed position and in use.

The dashed lines shown in the drawings illustrate environmental structure and form no part of the claimed design.
